UNITED STATES PATENT OFFICE

JOSEPH P. MINGLE, OF MUNCIE, INDIANA, ASSIGNOR TO BALL BROTHERS COMPANY, OF MUNCIE, INDIANA, A CORPORATION OF INDIANA.

WIRING MACHINE

Application filed September 8, 1931. Serial No. 561,674.

The present application relates to wiring machines, and more particularly to machines for fastening wire collars to the necks of jars. The primary object of the invention is to provide mechanical means for performing this operation. A further object of the invention is to provide mechanical means for twisting together a pair of wire ends. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a perspective view of one embodiment of my invention;

Fig. 2 is a fragmental side elevation, partly in section, of the wire manipulating means, the jar holding means, and the jar ejecting means;

Fig. 3 is a fragmental side elevation of the main actuating cylinder and certain associated parts, portions thereof being shown in section;

Fig. 4 is a perspective view of the jar holding means, the actuating means therefor, the twister head, and the means for actuating said twister head to flatten the wire ends;

Fig. 5 is a fragmental plan of the wire manipulating means, together with the actuating means therefor and the jar ejecting means;

Figs. 6 and 7 are fragmental plans of the wire manipulating mechanism in various positions;

Fig. 8 is a longitudinal horizontal section through the twister head;

Fig. 9 is a perspective view of the twister head;

Fig. 10 is a broken perspective of certain details of the twister head;

Fig. 11 is a longitudinal section, upon an enlarged scale, of the outer end of the twister head;

Fig. 12 is a broken perspective view of a

jar, showing the collar in broken lines before manipulation by the machine; and in solid lines after manipulation;

Fig. 13 is a plan of the twisted wire ends after manipulation by the machine; and

Fig. 14 is a diagrammatic view illustrating the fluid pressure operating mechanism, together with the control valves and fluid pressure connections therefor.

Referring more particularly to the drawings, it will be seen that I have illustrated a machine comprising a pedestal 20 upon which is carried a vertical column 21. A collar 22 which carries a platform or table 23 is suitably secured to said column 21 by set screws 25, or the like. A chute 24 leads from said platform to a work table, or the like. While the table 23 is inherently adjustable upon the column 21, because of the character of the means whereby said table is secured to said column, it is not intended that said table shall be adjusted during ordinary use of the machine.

A collar 26 is slidably mounted upon said column 21, said collar being rigidly secured to one end of a brace 27 to the opposite end of which is secured a further collar 28 likewise slidably mounted upon the column 21. Said collar 28 carries an element 29 in which is secured the lower end of a threaded rod 30 projecting through an unthreaded aperture in an arm 19 secured to the upper end of the column 21. A hand wheel 31 is internally threaded and is received upon the upper end of said rod 30, the hub of said wheel bearing against the upper surface of the arm 19. Said brace 27 and collars 26 and 28, together with the mechanism carried thereby, are thus supported by the element 29, rod 30, and hand wheel 31 bearing upon the arm 19, and the vertical position of all mechanism carried by said collars 26 and 28 and said brace 27, with respect to said table 23, is adjustable by actuation of the wheel 31.

The machine is primarily designed for co-operation with jars of the general type of that illustrated at 32, such jars being formed with reduced necks such as 33. The bail for securing the top to the jar is connected to a pair of perforated ears carried by a wire 34. For

many years, the wires 34 have been secured to the jars by a manual operation. The wires 34, carrying the ears 35, and formed to a general U-shape, are positioned on the jars in the manner illustrated in broken lines in Fig. 12. An operator then grasps the projecting ends 36 and 37, bends them toward each other until they overlap, and then, grasping the overlapped wire ends with a pair of pliers, rotates 10 the jar, while holding the wire ends against rotation therewith. The operator then bends the projecting ends of the twisted wires backwardly toward the surface of the jar.

When working with a machine of the character illustrated herein, the operator merely places the U-shaped wire in position upon the jar neck, and then moves the jar across the platform 23 into cooperative relation with the machine. All of the rest is done by the machine which, after the wires have been twisted and properly flattened, ejects the jar, and starts the same on its way down the chute 24.

25 A bracket 38 carried by the collar 28 is provided with a pair of spaced, substantially parallel arms 39 and 40. Adjacent its free end, the arm 39 is formed with an aperture in which is oscillably mounted an element 41. A portion 42 of said element 41 (see Fig. 2) 30 is located below the arm 39 and is bifurcated, as shown. That portion of element 41 which is positioned above the arm 39 carries a bell crank lever 43 the two arms of which are indicated at 44 and 45.

35 A member 46 is pivotally secured, by means of a pin 47, between the furcations of the portion 42 of the element 41. To the arm 45 of the lever 43 is pivotally secured, by a pin 48, a clamp 49 in which is received a finger 50 formed at its free end with a wire-receiving 40 notch 251 (see Fig. 14). Said clamp member 49 likewise carries a threaded rod 51 to the lower end of which is secured an arm 52, the free end of said arm being bent inwardly, as is clearly shown in the drawings. Said rod 51 is secured to the member 49 by a wing nut 53, the arrangement being such that said rod 51 may be clamped against rotation with respect to the member 49, or may be adjusted 45 rotatably with respect to said member 49.

The finger 50 carries a pin 54 for a purpose later to be described, and said pin is adjustable axially.

50 A tension spring 55 is secured at its one end to said member 49 and at its opposite end to a pin 56 carried adjacent the extremity of the arm 44 of the bell crank lever 43.

The arm 40 is likewise apertured adjacent its free end, and an element 57 is oscillably mounted in said aperture. Said element 57 is provided with a portion 58 positioned below the arm 40, and a member 62 is pivotally secured by a pin 63 between the furcations of said portion 58.

65 A bell crank lever 59 having arms 60 and

61 is secured to said element 57, and a pin 64 pivotally mounts upon said arm 61 a clamp member 65 in which is received a finger 66 similar to the finger 50. A rod 67 carries an arm 68 similar to the arm 52, and said rod 67 is secured to the element 65 by a wing nut 69 in the manner above described with respect to the rod 51.

70 As is clearly shown in Fig. 5, the arms 52 and 68 project toward each other and normally overlap slightly. A tension spring 70 has its one end secured to the member 65 and has its opposite end secured to a pin 71 adjacent the extremity of the arm 60 of the bell crank lever 59.

75 To one end of a cross head 72 a rod 73 is pivoted, as at 74, said rod 73 being secured to the member 46. A rod 75 is secured to the member 62 and is pivoted as at 76 to the opposite end of the cross head 72. Obviously, 80 movement of the cross head 72 toward the right or left as viewed in Figs. 5 to 7 will effect oscillation of the elements 41 and 57, for a purpose later to be explained. Said cross head is actuated through the medium of a rod 77 carried by a piston 187 in a fluid pressure cylinder 78. (See Figs. 2 and 14.)

85 A valve 79, which will be described in more detail hereinafter, includes a stem 80 which projects into cooperative relation with the pin 54. The twister head is indicated generally by the reference numeral 81 in Fig. 3, and is illustrated in some detail in Figs. 8 to 11 inclusive. This twister head 95 comprises the sleeve 82 formed internally with threads 83, and externally threaded at its one end for cooperation with the internally threaded skirt 84 of a member 85 to which is secured a stem 86 by means of a lock nut 87. A housing 88 encloses said sleeve and said member, said housing being formed at its one end with an inwardly turned flange 89 cooperating with a forwardly facing shoulder 90 on the sleeve 82. The rear end of the housing 88 is closed by an element 91 formed with a pair of oppositely disposed slots 92 for a purpose later to be described.

100 Cooperatively associated with the sleeve 82 is a gripper head comprising an element 93 formed with a reduced neck 94, said neck being externally threaded for engagement with the internal threads of a socket 252 formed in an end of a member 95, said member 95 being provided with external threads engageable with the threads 83 of the sleeve 105 82. The element 93 is formed with a pair of substantially diametrically opposed wire-receiving slots 96 and 97. The open ends of the slots 96 and 97 are circumferentially directed, and the element 93 is formed with 110 forwardly directed cam surfaces 98 leading from the open ends of said slots 96 and 97. The slots 96 and 97 are axially protected in a forward direction by tongues 99 and 100, respectively. The element 93 is formed with 115 120 125 130

a radially projecting flange 101 which is normally spaced from the forward end of the sleeve 82 to provide a socket, as is clearly shown in Fig. 8.

5 At its rearward end, the member 95 is provided with a reduced stem 102 about which is sleeved a torsion spring 103, one end of said spring being engaged in a socket in the adjacent end of the member 95, and the opposite end 104 of said spring being received in any one of a plurality of slots 106 formed in a nut 105 threaded into the rear end of the sleeve 82. It will be obvious that the tension of the spring 103 may be varied by positioning the end 104 of said spring in one or another of the slots 106.

The element 93 is, as will be obvious from an inspection of Fig. 11, adjustably mounted in the member 95, and said element is formed 20 with an internally threaded bore 253 in which is threaded a jam screw 254, whereby said element may be held in adjusted position with respect to said member 95.

Referring, now, to Figs. 2 and 5, it will 25 be seen that the collar 28 carries a bracket 107 in which is journaled the shaft 86. Said shaft carries a bevel gear 108 meshing with a bevel gear 109 carried on the shaft 110 journaled in a bracket 111 carried by said collar 28. A pinion 112 is secured to said shaft 110, preferably beyond said bracket 111.

A main fluid pressure motor is carried by the collar 26 and comprises a cylinder 113 (Fig. 3) in which is operatively mounted a piston 114 (Fig. 14) having a stem 115 which carries a rack 116 meshing with one side of the pinion 112. A second rack 117 is reciprocably mounted in a guide 118 and is provided on its opposite edges with two series of teeth 119 and 120. The teeth 119 mesh with that side of the pinion 112 opposite the side with which the rack 116 meshes, while the teeth 120 of the rack 117 mesh with a pinion 121 loosely mounted upon the stem 122 of a rotary valve 123 (see Fig. 14). Said valve 123 is enclosed in a valve casting 124 carried on the bracket 111 (Fig. 5). The teeth of the pinion 121 are preferably formed in the manner shown in Fig. 5, being 40 widened adjacent one end of the pinion, as indicated at 125, whereby said teeth are somewhat strengthened. Said end of the pinion 121 is provided with ratchet teeth 126 for cooperation with ratchet teeth 127 formed upon a collar 128 secured to the stem 122 by a pin 129, or the like. Obviously, said collar 128 is slidably mounted on the stem 122, and a compression spring 130 urges said collar toward said pinion 121, said spring abutting 50 at its one end against said collar and at its opposite end against a nut 131 adjustably mounted on said stem 122. Obviously, this arrangement is such that, when the pinion 121 is driven in a counter clockwise direction 60 at its one end, the stem 122 and valve 123 will be rotated; but when said pinion 121 is driven in a clockwise direction, as viewed in Fig. 3, said stem and valve will not be rotated.

A bracket carried by the collar 28 terminates in a sleeve 132 in which is adjustably mounted an arm 133 carrying a vertically disposed sleeve 134 (Figs. 1 and 3). A stem 135 is reciprocably mounted in said sleeve 134, and the lower end of said stem carries a head 137 of relatively soft material, said head being adapted to enter the neck 138 of a jar 32 to hold said jar, at times, against movement on the platform 23. Said sleeve 134 is formed with a longitudinally extending, laterally opening slot 145 through which projects a pin 144 upon which is mounted a grooved wheel 136 (Fig. 4). A finger 139 carried by a rock shaft 140 engages in the groove of said wheel 136 whereby, when said shaft 140 is rocked in a counter clockwise direction as viewed in Fig. 3, said finger 139 co-acts with said wheel 136 to lift said stem 135 and head 137.

The rock shaft 140 carries a cam finger 141 cooperable with a cam block 142 mounted at the upper end of a projection 143 carried on the stem 115, and cooperable also with a dog 146 pivoted at 147 on said projection. An arm 148, rigid with said dog 146 has attached thereto a spring 149 operable to maintain said dog normally in the position illustrated in Fig. 3.

A second rock shaft 150, likewise carried by said collar 28, is mounted below said shaft 140 (see Figs. 3, 4, and 5) and carries a fork 151 engageable in the slots 92 of the member 91 (see Fig. 8). A clamp member 249 adjustably secured to the rock shaft 140 is provided with a finger 250 which engages the bearing for said shaft 150 to limit the clockwise movement of the shaft 140 and consequently to limit the downward movement of the stem 135 and head 137.

The rock shaft 150 carries at its end remote from the fork 151 a housing comprising a pair of spaced walls 152 between which extends a pivot pin 153 upon which is pivotally mounted an actuator 154. A compression spring 156 is received between the base 157 of said housing and the upper end 158 of said member 154, said spring tending to hold the lower portion of said actuator in contact with a stop element 159. At its extremity the lower portion of said actuator is provided with a rearwardly projecting cam member 160, said cam member being formed with a downwardly and rearwardly extending cam surface 162 and with an upwardly and laterally directed cam surface 161. A stud 163 carried upon the stem 115 cooperates with said surfaces 161 and 162 in a manner later to be described.

I have illustrated a guide sheave 164 cooperatively associated with the rack 116, and

it is to be understood that guide means of any desired character will be provided to prevent undue lateral motion of reciprocating parts.

5 A bracket 165 (Fig. 1) suitably secured to the collar 22 carries a fluid pressure motor comprising a cylinder 166 in which is operatively received a piston 167 (Fig. 14) provided with a stem 168, the outer end of said stem being guided and supported in a bearing 169 carried by the platform 23 (Fig. 2). A collar 170 is adjustably secured to said stem 168, and said collar carries an arm 171 projecting upwardly through a slot 172 formed in the platform 23, said arm carrying, at a point above the surface of said platform 23 a yoke 173. The function of this mechanism will be described hereinafter.

20 The present machine is adapted for operation by fluid under pressure, and a suitable source of pressure fluid (not shown) will, of course, be provided. Referring to Fig. 14, it will be seen that I have illustrated a main line 174 leading from the fluid source and having connected thereto a conduit 175 connected to the inlet port 176 of the valve casing 79 (see Figs. 1 and 6). Said casing is likewise provided with an exhaust port 177 and a valve operating port 178. Said valve casing is further provided with a port 255 which is located substantially opposite the port 176. Within said casing is operatively received a piston valve 179 formed with a circumferential groove 180 with which communicates a longitudinally extending branch 181. Said valve 179 is connected to the stem 80 and is reciprocable in the casing 79. The groove 180 is so positioned that, at one extremity of the stroke of said valve 179 said groove registers with the exhaust port 177; while the branch 181 is so located as to provide communication, in all positions of the valve 179, between the groove 180 and the port 255. When the valve 179 is moved downwardly in the casing 79, as viewed in Fig. 14, the groove 180 is moved out of registry with the exhaust port 177 and into registry with the inlet port 176, whereby communication is provided between the conduit 175 and a conduit 183 connected to said port 255. The valve 179 is provided with a second circumferential groove 182.

55 The conduit 183 is likewise connected to an inlet port 184 of the rotary valve casing 124, (Figs. 1, 3, and 5) and a branch 185 leading from the conduit 183 is connected to a port 186 in the cylinder 78 (Figs. 1, 2, and 5). Said cylinder 78 operatively receives a piston 187 to which is connected the stem 77 which carries the cross head 72. A coil spring 189 surrounds said stem 77 and abuts at its one end against the upper surface of the piston 187 and at its opposite end against the closure head of the cylinder 78, whereby said piston 187 is normally held in the posi-

tion illustrated in Fig. 14. A passage 188 provides communication between that portion of the interior of the cylinder 78 above the piston 187 and the atmosphere, and the port 186 is located below said piston 187. It 70 will be obvious that fluid under pressure supplied through the port 186 will cause upward movement of the piston 187 as viewed in Fig. 14, thus compressing the spring 189 and forcing the air within the cylinder 78 out through the passage 188; and that, after the port 186 is opened to atmosphere, the spring 189 will return the piston 187 to the position illustrated in Fig. 14, air being drawn into the cylinder 78 through the passage 188. 75 80

The rotary valve casing 124 is formed with a longitudinally extending bore 190 provided with a plurality of branches 191, 192, and 193. The valve 123 is provided with a plurality of angularly and axially spaced transverse passages 194, 195, and 196. The passage 194 is so positioned that, in one position of the valve 123, said passage 194 establishes communication between the branch 191 and a port 197 in said casing 124; the passage 195 is so positioned that in another position of the valve 123, said passage establishes communication between the branch 192 and a port 198; and the passage 196 is so positioned that, in still another position of the valve 123, said passage 196 establishes communication between the branch 193 and a port 199. 90 95

A conduit 200 is connected at its one end to said port 199 and at its opposite end to a port 201 formed in a closure plug for an end 100 of a valve casing 202 (Figs. 1 and 3), said valve casing being provided with a second port 203 separated from said port 201 by a valve seat with which cooperates a valve 204. Said valve 204 carries a stem 205 projected outwardly of the casing 202, and an actuating lever 206 cooperates with the projecting portion of the stem 205, said lever being pivoted at 207 to said casing 202. A compression spring 208 engages said valve 204 and biases the same toward closing association with the seat formed in the casing 202. It will be obvious that rotation of the lever 206 in a clockwise direction about its pivot 207 will depress the valve 204, compressing the spring 208 and establishing communication between the ports 201 and 203; and that, when said lever 206 is released, the spring 208 will return the valve 204 to the illustrated position in which communication between the ports 201 and 203 110 115 120 is closed.

In Fig. 14, I have shown the lever 206 in direct contact with the upper end of the stem 205. I prefer, however, to use the arrangement illustrated in Fig. 3 in which the lever 125 206 carries an adjustable abutment pin 248 which pin contacts the upper end of the stem 205.

A conduit 209 provides communication between the port 203 of valve casing 202 and an 130

- actuating port 210 formed in one end of a piston valve casing 211 (Fig. 1). Said casing 211 is formed in one side wall with a pair of outlet ports 212 and 213. A second actuating port 214 is formed in the end of said casing opposite that end in which the port 210 is formed; and a pair of exhaust ports 215 and 215' are formed in a wall of the casing 211 substantially opposite the ports 212 and 213.
- 10 Said casing is likewise formed with an inlet port 216 with which communicates a branch 217 of a conduit 218 connected to the fluid supply line 174.
- Within said casing 211 is mounted a piston valve 219 of well known form, said valve being so constructed that, in the position illustrated, communication is established between the inlet port 216 and the outlet port 213, and between the outlet port 212 and the exhaust port 215; while, in its opposite position, said valve establishes communication between the inlet port 216 and the outlet port 212 and between the outlet port 213 and the exhaust port 215'.
- 25 A conduit 220 is connected to the outlet port 212 and to a port 221 formed in the lower end of the main fluid pressure motor cylinder 113 (Figs. 1 and 3); and a conduit 222 is connected to the outlet port 213 and to a port 223 in the upper end of said cylinder 113. A conduit 224 is connected to the actuating port 214 and to one end of a passage 225 traversing a projection 226 formed at the upper end of the cylinder 113. A conduit 227 is connected to the opposite end of said passage 225 and to said branch 217. The piston rod 115 intersects, and normally closes said passage 225, but said rod is formed, at a point adjacent the piston 114, with a transverse passage 228 therethrough. It will be obvious that, when said passage 228 registers with the passage 225, communication will be established between the source of fluid under pressure and the actuating port 214 of the casing 211.
- 35 A conduit 229 has its one end connected to the port 197 of the valve casing 124, and the opposite end of said conduit 229 is connected to one actuating port 230 of a piston valve casing 231, (Fig. 1) said casing 231 being substantially identical with the casing 211. Said casing 231 is provided with the actuating ports 230 and 232, the outlet ports 243 and 244, exhaust ports 241 and 242, and inlet port 238. A conduit 233 connects the port 232 with one end of a passage 234 traversing a sleeve 235 formed on the cylinder 166, (Figs. 1, 2, 5 and 6) and a conduit 236 connects the opposite end of said passage 234 with the conduit 218. The passage 234 is controlled by the piston rod 168, said piston rod being formed with a transverse passage 237 adapted, in one position of the piston 167, to register with said passage 234. Fluid under pressure is supplied to the casing 231 through
- the conduit 218 and the branch 239 connected to the port 238. A piston valve 240, substantially identical with the valve 219, is operatively mounted in said casing 231, and said valve 240 is operable to control the ports of said valve casing 231 in the manner described with respect to the valve 219.
- 40 A conduit 245 connects the outlet port 243 to a port 256 in the lower end of the cylinder 166; and a conduit 246 connects the port 244 to a port 247 formed in the upper end of the cylinder 166.
- 45 A conduit 257 connects the port 198 of the valve casing 124 with the actuating port 178 of the valve casing 79.
- 50 The operation of the disclosed machine is as follows: The parts being in the positions illustrated in Figs. 3 and 5, a jar 32, with which has been associated a U-shaped wire 34, is placed upon the platform 23 and is moved toward the cross head 72. The jar engages the bent ends of the arms 52 and 68 and, as the jar is moved farther, said arms 52 and 68 are crossed, thus centering and guiding the jar. Continued movement of the jar causes the arms 52 and 68 to rotate, and to carry with them the clamp members 49 and 65 to which they are secured, said clamp members rotating about their axes 48 and 64. The fingers 50 and 66 are thus rotated and, as said fingers are carried with the clamp members, said fingers respectively receive within their notches the wire ends 37 and 36. Further rotation of the fingers about the axes 48 and 64 will move the wire ends 36 and 37 toward each other, and eventually cross said wire ends. As the jar 32 is moved to its ultimate inward position, the parts assume the positions illustrated in Fig. 6.
- 55 As the parts attain this position, the pin 54 carried by the finger 50 engages the valve stem 80 to move the valve 179 into a position in which the groove 180 provides communication between the ports 176 and 225. Fluid is thus supplied through the line 174, 175, 176, 180, 255, 183, 185, and 186 to the cylinder 78 to move the piston 187 upwardly as viewed in Fig. 14. This movement advances the cross head 72, moving the same to the right as viewed in Figs. 5, 6, and 7. Such movement of the cross head 72 results, because of the provision of the rods 73 and 75, in counter clockwise rotation of the member 41 and in clockwise rotation of the member 58, thus effecting corresponding rotation of the bell crank levers 43 and 59. Such rotation of the levers 43 and 59 retracts the clamp members 49 and 65, and the fingers 50 and 66 are, of course, carried with said clamp members, the parts assuming the positions illustrated in Fig. 7.
- 60 When the machine is at rest, and before the jar 32 has been advanced in the manner above described, the piston rod 115 is in its lowermost position. Said piston rod carries
- 65

- 125
- 130

an abutment member which, in the lowermost position of the piston rod 115, engages the lever 206 to hold the same in depressed position, whereby the valve 204 is held in open position. At this time, the valve 123 is in the position illustrated in Fig. 14, in which the passage 196 establishes communication between the branch 193 and the port 199.

10 Simultaneously with the supply of fluid to the cylinder 78, fluid under pressure flows through the line 174, 175, 176, 180, 255, 183, 184, 190, 193, 196, 199, 200, 201, 203, 209, and 210 to the valve casing 211, thus moving the piston valve 219 to the position opposite that illustrated in Fig. 14. Such movement of the valve 219 establishes communication between the ports 216 and 212, and establishes communication between the ports 213 and 215'. Fluid under pressure is thus permitted to flow through the line 174, 218, 217, 216, 211, 212, 220, and 221 to force the piston 114 to move upwardly in the cylinder 113, the fluid contained within said cylinder 113 above the piston 114 being expressed to the atmosphere through the line 223, 222, 213, 211, and 215'.

As the piston 114 moves upwardly, the block 142 (see Fig. 3) releases the finger 141, thus permitting the rock shaft 140 to rotate in a clockwise direction as viewed in Fig. 3, and permitting the stem 135 and head 137 to drop, the head 137 entering the neck 138 of the jar 132 to hold said jar against movement. Upward movement of said piston rod 115 carries with it the rack 116, whereby the pinion 112 is actuated to rotate the shaft 110 in a counter clockwise direction as viewed in Fig. 3. This movement of the shaft 110 is translated, through the bevel gears 109 and 108, to clockwise rotation of the shaft 86, as viewed from the left of Fig. 5.

As the shaft 86 rotates, it carries with it the member 85 and the sleeve 82 (see Fig. 8). The head 93 is likewise slightly rotated, whereby the wire ends 36 and 37 are engaged in the notches 96 and 97, respectively. As soon as the bases of the notches 96 and 97 engage the wire ends, whereby the stiffness of the wire opposes rotation of the head 93, such rotation of the head is arrested or retarded, while the sleeve 82 continues to rotate at its original speed. The relative movement of the sleeve 82 with respect to the head 92 is translated, by the co-action of the threads 83 with the threaded element 95, into retractile movement of the head 93, whereby the wires are gripped or clamped between the tongues 99 and 100 and the forward end of the sleeve 82. When the wires have been so clamped, further relative movement of the sleeve 82 with respect to the head 93 is prevented, and the head 93 is rotated with said sleeve.

The parts are so proportioned that a full upward stroke of the piston rod 115 and rack 116 will effect substantially one and one-half revolutions of the shaft 86, whereby the wire ends 36 and 37 are twisted together in the manner, and to the degree, clearly shown in Figs. 12 and 13.

As the piston rod 115 moves upwardly, the dog 146 engages the finger 141 to insure initiation of the clockwise movement of the rock shaft 140. Said dog 146 is yieldable, however, and does not enforce movement of the finger 141.

Just before the piston rod 115 reaches the upper limit of its stroke, the abutment 163 contacts the surface 161 of the projection 160 of the member 154 (Fig. 4). Because of the shape of said surface, however, the only result of such engagement is a counter clockwise movement of the member 154, as viewed in Fig. 4, whereby the spring 156 is compressed; and as soon as the abutment 163 has passed the projection 160, the spring 156 returns the element 154 to the position illustrated in Fig. 4.

The meshing engagement of the pinion 112 with the teeth 119 of the rack 117 results in downward reciprocation of said rack 117 as the rack 116 moves upwardly. Downward movement of the rack 117 results, because of the meshing engagement of the teeth 120 with the pinion 121, in clockwise rotation of said pinion 121. Because of the construction of the ratchet teeth 126 and 127 and because of the fact that the pinion 121 is loose on the stem 122, the pinion 121 turns freely without affecting the stem 122 or the valve 123.

Of course, as soon as the piston rod 151 starts upwardly, the lever 206 is released, and the valve 204 is moved to closed position by the spring 208. Since the passage 225 is closed by the piston rod 115, however, the valve 219 will be held in the position above described, opposite that illustrated in Fig. 14.

As the piston rod 115 reaches the upper limit of its stroke, the passage 228 registers with the passage 225, thus establishing communication between the source of fluid supply and the port 214, as follows: 174, 218, 217, 227, 225, 228, 224, and 214. The valve 219 is thus moved to the position illustrated in Fig. 14, whereby fluid is supplied through the line 174, 218, 217, 216, 211, 213, and 223 to the upper end of the cylinder 113, whereby downward movement of the piston 114 is initiated, the lower end of the cylinder 113 being connected to the atmosphere through the line 221, 220, 212, 211, and 215. Of course, the stem 205 has a relatively sloppy fit in the valve casing 202, whereby when the valve 204 is closed, pressure in the conduit 209 will bleed to the atmosphere.

As the piston 114 starts downwardly, the rack 116 cooperates with the pinion 112 to

rotate the shaft 110 in a clockwise direction, thus rotating the shaft 86 and the head 93 in a counter clockwise direction to release the wire ends from the slots 97 and 98 (see Fig. 5 3). The wire ends are released upon substantially one-fourth revolution of the head 93. At substantially the moment when the wire ends are released from the slots 96 and 97, the abutment 163 engages the surface 162 of the projection 160 to rotate the rock shaft 150 in a counter clockwise direction as viewed in Fig. 3. Such movement of the rock shaft 150 is translated, by the fork 151, into forward movement of the housing 88. This 10 movement is in the nature of a kick, the housing being shifted quickly forward to engage with the projecting wire ends 36 and 37 and to bend them backwardly substantially into contact with the surface of the jar 32. As the 15 piston rod continues its movement downwardly, the abutment 163 moves past the projection 160 and releases the same, the housing 88 being returned to its initial position.

Clockwise rotation of the pinion 112 effects 20 upward movement of the rack 117 which, in turn, causes counter clockwise rotation of the pinion 121. As the pinion 121 is thus rotated, the ratchet teeth 126 and 127 engage, and the 25 stem 122 is rotated with said pinion. As the stem 122 rotates, the valve 123 being carried therewith, the passage 196 is moved out of registry with the branch 193 and port 199, and shortly after the above described shifting of the housing 88, the passage 194 moves 30 into registry with the branch 191 and the port 197. Fluid is thus supplied through the line 174, 175, 176, 180, 255, 183, 184, 190, 191, 194, 197, 229, and 230 to the valve casing 231, whereby the piston valve 240 is moved to the 35 position opposite that illustrated in Fig. 14. In the position thus assumed by the valve 240, communication is provided between the inlet port 238 and outlet port 243, and fluid is supplied, through the line 174, 218, 239, 40 238, 231, 243, 245, and 256 to the lower end of the cylinder 166, as viewed in Fig. 14.

At substantially this moment, the lower surface of the dog 146 (Fig. 3) engages the finger 141 to rotate the rock shaft 140 in a 45 counter clockwise direction to elevate the stem 135 and head 137 to release the jar 32.

The fluid supplied to the lower end of the cylinder 166 forces the piston 167 upwardly, as viewed in Fig. 14, whereby the yoke 173 is 50 moved downwardly and to the right as viewed in Fig. 5 through the slot 172 to carry the jar 32 across the platform 23 and into the chute 24.

As the piston 167 reaches the limit of its 55 stroke in this direction, the passage 237 in the piston rod 168 registers with the passage 234, whereby fluid is supplied through the line 174, 218, 236, 234, 233, and 232 to the upper end of the valve casing 231 as viewed 60 in Fig. 14, it being understood that continued

rotation of the valve 123 has moved the passage 195 out of registry with the port 198. The valve 240 is thus shifted to the position illustrated in Fig. 14 in which fluid is supplied to the upper end of the cylinder 166 70 through the line 174, 218, 239, 238, 231, 244, 246, and 247, to retract the piston 167.

As the rack 117 continues to move upwardly, the passage 195 comes into registry with the branch 192 and the port 198, whereby 75 fluid is supplied through the line 174, 175, 176, 180, 255, 183, 184, 190, 192, 195, 198, 257, and 178 to return the valve 179 to the position illustrated in Fig. 14. In this position, the groove 180 and the branch 181 are in communication with the exhaust port 177. Such movement of the valve 179 uncovers a port 80 258 in the casing 79, thus venting the lower part of said casing and the conduit 257 to the atmosphere. 85

As the piston 114 reaches the lower limit of its stroke, the passage 196 is again brought into communication with the branch 193 and the port 199. Thus, the valve casing 202 is 90 vented through the line 201, 200, 199, 196, 193, 190, 184, 183, 255, 181, 180, and 177. Thus, also, the cylinder 78 is vented through the line 186, 185, 183, 255, 181, 180, and 177, and the spring 189 is permitted to return the piston 187 to the position illustrated in Fig. 14, 95 thus returning the cross head 72 to the position of Fig. 5. At this time, the parts are all in the positions illustrated in Figs. 3 and 5, and the machine is ready to receive another jar. 100

I claim as my invention:

1. In a device of the character described, means engageable with a pair of wire ends to cross said ends, and a twister head associated with said means, said twister head comprising an element provided with two notches to laterally receive said respective wire ends, and means for clamping said wire ends in said notches each against one wall of said slot, and means for rotating said head. 110

2. In a device of the character described, wire twisting mechanism comprising an element provided with a wire-receiving recess arranged to receive a wire by lateral projection, means associated with said element and shiftable to engage a wire and clamp the same within said recess against one wall of the recess, and means for rotating said element. 115

3. In a device of the character described, wire twisting mechanism comprising a head formed with a circumferentially extending wire-receiving slot opening forwardly at its one end, a sleeve associated with said head, means for rotating said head in opposite directions, and means for effecting opposite relative axial movement between said head and sleeve upon relative rotary movements thereof in opposite directions, whereby a 130

wire received in said slot is caused to be clamped in said slot by said sleeve.

4. In a device of the character described, wire twisting mechanism comprising an internally threaded sleeve, a head mounted within said sleeve and threaded for cooperation with the threads of said sleeve, said head being formed with a circumferentially extending wire-receiving slot, and means for rotating said sleeve in opposite directions.

5. In a device of the class described, wire twisting mechanism comprising an internally threaded sleeve, a head, a portion of said head being received within said sleeve and threaded for cooperation with the threads of said sleeve, said head being provided, without said sleeve, with a circumferentially extending wire receiving slot opening, at one end, through the free end of said head, and means for rotating said sleeve in the direction of said one end of said slot whereby said threaded elements cause said head to move inwardly axially of said sleeve to cause said sleeve to clamp a wire in said slot.

6. In a device of the class described, wire twisting mechanism comprising an internally threaded sleeve, a head, a portion of said head being received within said sleeve and threaded for cooperation with the threads of said sleeve, said head being provided, without said sleeve, with a circumferentially extending wire receiving slot opening, at one end, through the free end of said head, means for rotating said sleeve in the direction of said one end of said slot whereby said threaded elements cause said head to move inwardly axially of said sleeve to cause said sleeve to clamp a wire in said slot, and resilient means for returning said head to its initial position.

7. In a device of the class described, wire twisting mechanism comprising an internally threaded sleeve, a head, a portion of said head being received within said sleeve and threaded for cooperation with the threads of said sleeve, said head being provided, without said sleeve, with a circumferentially extending wire receiving slot opening, at one end, through the free end of said head, a torsion spring engaging said sleeve and said head and biasing said head toward its position of maximum projection from said sleeve, and means for rotating said sleeve.

8. In a machine of the class described, a platform adapted to support articles carrying substantially U-shaped wires, means engageable by an article on said platform for crossing the ends of the wire carried by said article, means engageable with said crossed wire ends and operable to twist said ends together, and means for flattening the twisted wire ends against said article.

9. In a machine of the class described, a platform adapted to support an article hav-

ing a substantially U-shaped wire embracing it, means actuated by movement of said article in one direction on said platform to engage the ends of said wire and cross said ends, means for gripping said crossed wire ends, and means for rotating said gripping means to twist said wire ends together. 70

10. In a machine of the class described, a platform adapted to support an article having a substantially U-shaped wire embracing it, means actuated by movement of said article in one direction on said platform to engage the ends of said wire and cross said ends, means for gripping said crossed ends, means for rotating said gripping means to 75 twist said wire ends together, means for flattening said twisted wire ends against said article, and means for moving said article in an opposite direction on said platform.

11. In a machine of the class described, a platform adapted to support an article having a substantially U-shaped wire embracing it, means actuated by movement of said article in one direction on said platform to engage the ends of said wire and cross said 90 ends, means actuated by such actuation of said means to retract said crossing means from contact with said crossed ends, means for gripping said crossed ends after retraction of said crossing means, and means for 95 rotating said gripping means to twist said wire ends together.

12. In a machine of the character described, a platform adapted to support an article having a substantially U-shaped wire 100 embracing it, means actuated by movement of said article in one direction on said platform to engage the ends of said wire and cross said ends, means for gripping said crossed wire ends and twisting said ends 105 about each other, means actuated by operation of said crossing means to operate said gripping and twisting means, means for returning said last-named operating means to initial position, and means actuated by return movement of said operating means to move said article away from said twisting means. 110

13. In a machine of the character described, a platform adapted to support an article having a substantially U-shaped wire 115 embracing it, means actuated by movement of said article in one direction on said platform to engage the ends of said wire and cross said ends, a twister head adapted to grip said crossed wire ends, means actuated by operation of said crossing means to cause said twister head to grip said wire ends and to twist the same, and means actuated by 120 operation of said crossing means to retract said crossing means before the twisting actuation of said head. 125

14. In a machine of the character described, a platform adapted to support an article having a substantially U-shaped wire 130

embracing it, means actuated by movement of said article in one direction on said platform to engage the ends of said wire and cross said ends, a twister head adapted to grip said crossed wire ends, means actuated by operation of said crossing means to cause said twister head to grip said wire ends and to twist the same, means actuated by operation of said crossing means to retract said 5 crossing means before the twisting actuation of said head, means for returning the operating means for said twister head to initial position, and means actuated by return movement of said operating means to move said 10 article away from said twister head.

15. In a machine of the character described, a platform adapted to support an article having a substantially U-shaped wire embracing it, a pair of pivotally mounted 20 arms disposed in the path of movement of said article, a finger movable with each of said arms, said fingers being adapted to engage said wire ends and cross the same as said arms are moved by said article, a twister 25 head associated with said fingers, a fluid pressure motor, control means for said motor including a valve adapted to be actuated by wire-crossing movement of said fingers, connections between said twister head and said 30 motor, whereby actuation of said valve by said fingers causes said motor to operate said twister head to twist said wire ends together, and means actuated by said motor for shifting said twister head axially to flatten said 35 wire ends against said article.

16. In combination, a seat for an article having a wire associated therewith, means engageable with said wire for bringing the ends thereof into juxtaposition, twister means engageable with said positioned wire ends and means engageable with said article to hold 40 operable to twist the same, and shiftable said article rigidly in place during the twisting operation.

45. 17. In combination, a seat for a receptacle having a wire associated therewith, means engageable with said wire for bringing the ends thereof into juxtaposition, twister means engageable with said positioned wire ends and operable to twist the same, and shiftable means engageable in the mouth of said receptacle to hold said receptacle rigidly in place 50 during the twisting operation.

18. In combination, a seat for a receptacle 55 having a wire associated therewith, means engageable with said wire for bringing the ends thereof into juxtaposition, twister means engageable with said positioned wire ends and operable to twist the same, and a reciprocable 60 plunger engageable in the mouth of said receptacle to hold said receptacle rigidly in place during the twisting operation.

19. In combination, a seat for a receptacle 65 having a wire associated therewith, means engageable with said wire for bringing the

ends thereof into juxtaposition, twister means engageable with said positioned wire ends and operable to twist the same, a reciprocable plunger having a head corresponding to the size and shape of the mouth of said receptacle, means for projecting said plunger head into said receptacle mouth prior to engagement of said twister means with said wire head, and means for withdrawing said plunger head from said receptacle mouth after 70 disengagement of said twister means from said wire ends.

20. In combination, a seat for a receptacle having a wire associated therewith, means engageable with said wire for bringing the ends thereof into juxtaposition, twister means engageable with said positioned wire ends and operable to twist the same, means associated with said twister means and operable to flatten said twisted wire ends after release thereof by said twister means, a reciprocable plunger having a head corresponding to the size and shape of the mouth of said receptacle, means for projecting said plunger head into said receptacle mouth prior to engagement of said twister means with said wire head, and means for withdrawing said plunger head from said receptacle mouth after 80 operation of said flattening means.

21. In a machine of the class described, a platform for supporting an article having a wire associated therewith, means for bringing the ends of said wire into juxtaposition, means engageable with said wire ends and operable to twist the same, and means for ejecting said article from said platform.

22. In a machine of the class described, a platform for supporting an article having a wire associated therewith, means for bringing the ends of said wire into juxtaposition, means engageable with said wire ends and operable to twist the same, shiftable means engageable with said article to hold the same in place during the twisting operation, and means for ejecting said article from said 105 platform.

23. In a machine of the class described, a platform for supporting an article having a wire associated therewith, power-operated means for bringing the ends of said wire into juxtaposition, power-operated means engageable with said wire ends and operable to twist the same, power-operated means shiftable into engagement with said article to hold the same in place during the twisting operation, power-operated means for ejecting said article from said platform, and means synchronizing said power-operated means whereby said holding means is caused to engage said article immediately before operation of said twisting means, and is caused to release said article immediately before operation of said ejecting means.

24. In combination, a seat for a receptacle having a wire associated therewith, twister 130

means engageable with the ends of said wire and operable to twist the same, and a reciprocable plunger engageable in the mouth of said receptacle to hold the same in place during the twisting operation.

25. In a machine of the class described, a platform for supporting an article having a wire associated therewith, means engageable with the ends of said wire and operable to twist the same, and means for ejecting said article from said platform.

26. Means for tying a wire about an article, comprising means engageable with the ends of such wire and operable to twist the same,

15

a motor for driving said twisting means, and means, actuated by movement of such article on said platform into cooperative relation with said twister means, for energizing said motor.

27. Means for tying a wire about an article, comprising power-operated means engageable with the ends of such wire and operable to twist the same, and means, actuated by movement of such article on said platform into cooperative relation with said twister means, for causing operation of said power-operated means.
